UNITED STATES PATENT OFFICE.

JOHN H. DUNSTAN AND ROBERT A. DAVIS, OF SLIDELL, LOUISIANA.

CONDENSER AND SEPARATOR FOR WOOD-IMPREGNATING RETORTS.

1,374,069.

Specification of Letters Patent.

Patented Apr. 5, 1921.

Application filed October 13, 1919. Serial No. 330,511.

To all whom it may concern:

Be it known that we, JOHN H. DUNSTAN and ROBERT A. DAVIS, of Slidell, in the county of Saint Tammany and State of Louisiana, have invented certain new and useful Improvements in Condensers and Separators, for Wood-Impregnating Retorts; and we do hereby declare the following to be a full, clear, and exact description 10 of the invention, such as will enable others skilled in the art to which it appertains to make and use the same.

In the art of wood impregnation the timber or other wooden material is run into a 15 retort which is then closed to make it practically air tight. Live steam is next admitted into the retort until the pressure of the steam in the retort reaches from 20 to 30 pounds per square inch, with a corresponding 20 temperature of from 250 to 275 degrees F. This pressure and temperature are maintained in the retort until the timber is heated to this temperature throughout. The steam is then blown out of the 25 retort as quickly as possible and a vacuum of as high degree as possible is created in the retort in the quickest possible time. The object of this vacuum is as follows: When the steam is blown out of the retort by its own 30 pressure the temperature of the wood with its contained moisture has a temperature of from 250 to 275 degrees F. The boiling point of water at atmospheric pressure being 212 degrees F., its boiling point is only 30 degrees F. at 30 inches of vacuum, (a perfect vacuum). Therefore the nearer we come to obtaining a perfect vacuum the lower the boiling point of water under the vacuum.

By obtaining a high and quick vacuum within the retort the boiling point of the water contained in the wood is lowered and this water is vaporized and drawn from the wood and carried off through the condenser. It is most essential that this vacuum be created quickly as otherwise the wood in the retort will lose its heat by radiation so that the temperature within the retort will be below the boiling point under the existing vacuum.

After the moisture is extracted from the

timber the retort is filled with oil, such as coal tar creosote, and more of this oil is pumped into the retort under pressure until the timber has absorbed the required amount.

In practising under Letters Patent No. 831,450, issued September 18, 1906, on the application of Cuthbert B. Lowry, and other processes, a second high quick vacuum is necessary after the injection of the oil so as to virtually withdraw the oil from the cells and pores of the timber, the portion remaining being completely absorbed, thus leaving no free oil and consequently avoiding waste of material.

From the foregoing it will be seen that one of the most important essentials to successful creosoting is the immediate creation of the highest attainable degree of vacuum. We have experienced difficulty in the use of the machinery heretofore proposed for quickly establishing this high vacuum. When a dry vacuum pump is connected to an ordinary engine steam condenser, or the condenser is used alone, and no appreciable quantity of air or other non-condensable gas is present, the vacuum may readily be created. In the retort used in wood impregnation, however, air and non-condensable gases are present besides the steam. These tend to carry the condensing water with them over to the pump which has to be used to create a prompt and high vacuum. This injures the dry pump and necessitates the use of a wet vacuum pump which is an expensive structure constantly becoming deranged.

We have overcome the difficulty by the structure illustrated conventionally in the drawing, where a barometric condenser 1, having a water inlet pipe 2, is adapted for connection by the elbow 3 with an impregnating tank. The lower extremity of the outlet 4 is constantly submerged in a hot well 5.

A barometric separator is indicated at 6. A pipe 7 leads directly from the condenser to the side and interior of the separator and its inner end opens downward in the separator, while a second pipe 8 establishes direct communication between the top of the separator and a vacuum pump. The outlet

9 of the separator also has its lower extremity constantly submerged in the hot well 5 which is equipped with an overflow 10. The outlet pipes 4 and 9 are in length not 5 less than 33 feet to overcome the tendency of the suction created by the vacuum to draw the water from the hot well and to allow the water to discharge constantly from the separator. The cross sectional area of 10 the separator is materially greater than the diameter of pipe 7 at the extremity which opens downward into the separator. In consequence when the water and non-condensable gases reach the separator the velocity 15 of their flow is greatly reduced and the force of the momentum acquired by the water in its flow, together with the force of gravity, causes the water to fall to the bottom of the separator (located well below the outlet of pipe 7) and be carried off through the sealed pipe 9, while the air and gases have to reverse their direction of travel and be drawn to the top of the separator 20 and through pipe 8 to the vacuum pump, their upward travel allowing further opportunity for particles of moisture to gravitate out of the stream. Thus it is practically impossible for the air and gases to carry water to the pump. The water accumulat- 25 30 ing in hot well 5 passes out through the overflow 10.

We are aware that it is not broadly novel to provide a separator between a condenser and a vacuum pump; but we are not aware 35 of any such structure prior to ours which is available for use in the art of wood impregnation. Means have heretofore been provided for regulating a vacuum proportionate to the quantity and temperature 40 of the water employed for condensation and the steam to be condensed. This has been accomplished by conducting the hot water from the separating chamber into the condensing chamber to control the temperature 45 of the fresh water in the condenser. All such constructions are foreign to our purpose. We seek to create a vacuum as quickly and as high as possible. Our condenser is directly connected to the retort and 50 to the separator and the separator is directly connected to the pump. The water discharged from both of them is waste.

Likewise those structures in which the pipe from the condenser enters the top of the 55 separator and the outlet to the pump leads from the side of the separator, are not capable of attaining our purpose, because the path of the fluids in the separator is in its most restricted area; they do not lose their 60 velocity but rather tend to increase it, and if they carry any material quantity of non-condensable gases, such as we have to care for, considerable of the water would be carried with the gases to the dry vacuum pump, 65 necessarily causing injury. We utilize the

largest area of the separator, from 7 downward, then up past 7 to the top and out at 8, reducing velocity and effectively eliminating the water.

A feature of particular importance resides 70 in the means for allowing the water to constantly discharge from the separator. In the first fifteen minutes of vacuum period the flow of water into the separator is approximately 300 gallons per minute. Manifestly a continuous discharge from the separator is essential in order to deal with this flow and at the same time avoid breaking the vacuum. By arranging our separator at a height of at least 33 feet above the 80 hot well the vacuum does not interfere with the free and constant flow from the condenser and separator. The ordinary commercial types of separators having means for periodically discharging the water 85 would not be available for our use. They may allow of discharging while under pressure but they cannot discharge while under vacuum as opening them to the atmosphere would break the vacuum. 90

We claim as our invention:

1. Means for creating a high and quick vacuum in a wood impregnating retort comprising a wood impregnating retort, a barometric condenser connected therewith, a 95 barometric separator, a pipe from the condenser discharging into the side of the separator, a pipe constantly leading directly from the top of the separator to a vacuum pump, a hot well, and a discharge pipe leading downward from said separator having its extremity submerged in said hot well, whereby said separator may constantly discharge while under a vacuum. 100

2. Means for creating a high and quick 105 vacuum in a wood impregnating retort comprising a wood impregnating retort, a barometric condenser connected therewith, a vertically disposed barometric separator, a pipe from the condenser entering the side 110 of the separator and discharging downward, a pipe constantly maintaining communication between the top of the separator and a vacuum pump, a subjacent hot well, and discharge pipe leading downward from 115 said condenser and separator having their extremities submerged in said hot well.

3. Means for creating a high and quick 120 vacuum in a wood impregnating retort comprising a wood impregnating retort, a barometric condenser connected therewith, a barometric separator, a pipe from the condenser discharging into the separator, a pipe constantly leading directly from the separator to a vacuum pump, a hot well, and discharge pipes leading downward from said condenser and separator having their extremities submerged in said hot well. 125

4. Means for creating a high and quick 130 vacuum in a wood impregnating retort

comprising a wood impregnating retort, a barometric condenser connected therewith, a barometric separator, a pipe from the condenser discharging into the separator, 5 means for directing the flow within the separator to separate the water from the air and gases, a pipe constantly leading directly from the separator to a vacuum pump, a hot well, and discharge pipes leading downward from said condenser and separator having their extremities submerged in said hot well.

In testimony whereof we have signed this specification.

JOHN H. DUNSTAN.
ROBERT A. DAVIS.
